UNITED STATES PATENT OFFICE

CHARLES H. SHULTZ, OF ST. JOSEPH, MISSOURI.

VAPOR-BURNER.

SPECIFICATION forming part of Letters Patent No. 380,356, dated April 3, 1883.

Application filed May 16, 1887. Serial No. 238,349. (No model.)

To all whom it may concern:

Be it known that I, CHARLES H. SHULTZ, a citizen of the United States, residing at St. Joseph, in the county of Buchanan and State 5 of Missouri, have invented a new and useful Improvement in Vapor-Burners, of which the following is a specification.

My invention relates to an improvement in vapor-burners; and it consists in the peculiar 10 construction and combination of devices, as will be more fully set forth hereinafter, and particularly pointed out in the claims.

In the drawings, Figure 1 is a vertical central sectional view of a vapor-burner embodying my improvements. Fig. 2 is a top plan view of the same.

A represents a hollow annular casting, which surrounds a vertical central opening, B, or space, that is entirely open from top to bottom. 20 From one side of the casting A projects an offset, C, which comprises a cap for the usual stand-pipe, D, and is provided with screw-threads to engage similar threads on the upper ends of the pipe, thus enabling the latter to be secured firmly to the casting A. The said casting constitutes the generating-chamber and receives its supply of oil from the stand-pipe D in the usual manner. From the opposite side of the generating-chamber extends a vapor- 30 pipe, E, to the lower end of which is attached a horizontal sleeve, F. G represents a needle-valve which works in the said sleeve and is adapted to open or close the aperture H at the inner end of the latter.

35 From the inner side of the cap C projects a horizontal ear, I. K represents an arm which depends from the generating-chamber on the side opposite the ear I, and the lower end of the said arm is bent outward at right angles to 40 form an ear, L.

M represents a combined mixing-chamber and burner-head, having a removable cap, N, on its upper side, provided with vertical openings O. The central portion of the said cap is 45 depressed to form an oil-cup, P. From opposite sides of the combined mixing-chamber and burner-head project horizontal ears R and R'. The ear R bears against the under side of the ear L and is secured thereto by a bolt or key, 50 S. The ear R' bears upon the upper side of the ear I and is secured thereto by a bolt or key, S'.

T represents a vertical bolt, which extends downward through a central opening in the cap N and also through an opening in the 55 lower side of the mixing-chamber and burner-head, and is provided with a clamping-nut, T'. This bolt serves to secure the cap rigidly in place on the upper side of the mixing-chamber and burner-head. Formed with and projecting from one side of the combined mixing-chamber and burner-head is a tube, U, the outer end of which is open, and is arranged on the same horizontal plane with and is presented 60 toward the inner end of the sleeve F. 65

By reference to Fig. 1 it will be seen that the mixing-chamber and burner-head is arranged directly below the generating-chamber A, and thereby the jets of flame from the openings O in the upper side of the burner-head are caused 70 to strike directly against the under side of the generating-chamber, so as to heat the same so intensely as to instantly vaporize the oil which is fed thereto.

It will be further noted that the exterior atmosphere communicates with the space between the bottom of the generating-chamber and the top of the burner, and thus insures a sufficient quantity of air to be constantly fed to the flames as they pass upward through the 80 opening B to cause complete and perfect combustion of the vapor.

The operation of my invention will be very readily understood. A small quantity of oil, previously placed in the cup N, is first ignited 85 to heat the burner and the chamber A, and a supply of oil is fed to the chamber A by the stand-pipe. As the oil reaches the chamber it is vaporized by the heat, and is fed through the pipe E and the sleeve F and directed upward 90 from the latter through the tube M into the burner. As the vapor passes through the tube air is sucked in with it and becomes commingled with the vapor in the burner, thereby rendering the same combustible by oxygenizing it. As the oxygenized vapor escapes 95 through the opening O it is burned, as previously described.

Particular stress is laid on the construction of the cap N with the depressed top forming the oil-cup; also the location of the burner and commingling-chamber below the generator A, with the openings O directly on a line with the bottom of the chamber A, whereby the jets

of flame from the openings O are caused to strike directly against the bottom before escaping upward or outward. The jets must strike the generator-chamber A before they 5 can escape. Waste heat is thereby avoided and vapor is more readily produced.

Having thus described my invention, I claim—

1. The combination, in a vapor-burner, of 10 the generating-chamber A, surrounding the vertical space or opening B, and the combined mixing-chamber and burner-head arranged under the generating-chamber, the said mixing-chamber and burner-head having the oil- 15 cup P formed in the top of its cap, substantially as described.

2. The burner-head having its cap formed with a depressed top, which provides a receptacle for oil to start the generation of vapor, 20 in combination with the generating-chamber arranged over the burner-head, substantially as described.

3. The generating-chamber A, surrounding the space or opening B, which is open from top 25 to bottom throughout, combined with the burner-head M, arranged vertically below the generator and separate and distinct from the same, the bottom of the generator-chamber and the top of the burner-head being sepa-

rated from each other by an intervening space, 30 so that the free draft of air is allowed up the opening B to assist combustion, said burner-head having openings O in the top, which openings are adapted to direct jets of flame against the bottom of the generator-chamber. 35

4. In combination with the generating-chamber A, the burner having its cap or top provided with the depressed portion forming the oil-cup, and the series of openings O in the cap outside the oil-cup, said openings O being 40 arranged directly below the bottom of the chamber A, as set forth.

5. In a vapor-burner, the generating-chamber A, surrounding a central air space or opening, combined with the burner arranged below 45 and out of contact with the under side of the generating-chamber, so that the burner will not close the central opening or space, but the latter will be entirely open at the top and bottom for the passage of air upward, as and for 50 the purpose set forth.

In testimony that I claim the foregoing as my own I have hereto affixed my signature in presence of two witnesses.

CHARLES H. SHULTZ.

Witnesses:

E. G. SIGGERS,
MYRTLE STALNAKER.
